United States Patent Office

Des. 212,352
Patented Oct. 8, 1968

212,352

CUP

Paul Davis, 18 Parsons Drive,
Swampscott, Mass. 01907

Filed Sept. 11, 1967, Ser. No. 8,551

Term of patent 14 years

(Cl. D9—220)

FIG. 1

FIG. 2

FIG. 3

FIG. 4

FIG. 1 is a side view of a cup showing my new design;
FIG. 2 is a top plan view thereof;
FIG. 3 is a bottom plan view thereof; and
FIG. 4 is a fragmentary side elevational view of a cup showing another embodiment of my new design wherein a plain indented bottom is employed.

I claim:

The ornamental design for a cup, as shown and described.
